UNITED STATES PATENT OFFICE.

ABNER D. THOMAS, OF LITTLE ROCK, ARKANSAS.

COTTON-ELEVATOR AND COTTON-GIN FEEDER.

SPECIFICATION forming part of Letters Patent No. 331,841, dated December 8, 1885.

Application filed May 12, 1885. Serial No. 165,245. (No model.)

To all whom it may concern:

Be it known that I, ABNER D. THOMAS, a citizen of the United States, residing at Little Rock, in the county of Pulaski and State of 5 Arkansas, have invented certain new and useful Improvements in Cotton-Elevators and Cotton-Gin Feeders, of which the following is a specification, reference being had therein to the accompanying drawings.

10 My invention relates to conveyers for cotton-gins, and the object of my invention is to provide mechanism for conveying and depositing uniform quantities of cotton or other material from a hopper to the floor above or to bins 15 suitably located.

The invention will be hereinafter described, and specifically set forth in the claims.

Figure 1 is a vertical section of my improved elevator. Fig. 2 is a side elevation of the 20 lower portion of the same, and Fig. 3 is a top view of the horizontal portion of the casing with a portion of the elevator-belt. Fig. 4 is a modification.

Like letters refer to like parts in all the 25 figures.

In the drawings, A represents the vertical, and A' the horizontal, portion of the elevator-casing, and at the bottom of the casing A is placed the hopper A². Within the casings A 30 and A' is located the endless elevator-belt B, which passes around the rollers B'. At a short distance above the hopper A², and secured to or a part of the casing, are adjustable brackets C, which support rollers C' for an endless belt, C², used to regulate the amount of cotton carried up by the elevator-belt B. The main shaft D of the elevator-belt B is located at the lower end of the casing A, and is provided 35 with a sprocket, D'. The shaft of the upper roller, C', carrying the belt C², is provided with a sprocket, D², which receives its motion from the sprocket D' through the sprocket-chain D³, and causes the adjacent surfaces of the elevator-belt B and of the belt C² to travel in 40 opposite directions, so that when too much cotton or any large lump of the same is raised by the belt B the rake-teeth c² of the belt C² force it back or pick off portions of the cotton, and thus cause a more uniform delivery 45 into the horizontal casing A'. The floor or bottom of said casing A' is provided with a series of openings, E, the size of which is regu-

lated by means of slides E', having their inner end beveled or cut diagonally to regulate the delivery or to close the openings, when desired.

The object attained by having the ends of the slides cut at an angle or diagonally across the path of the cotton, beginning with the smallest opening next to the hinged end cover, 50 F, and increasing in size at each following opening, are to feed several gin stands or hoppers, or other elevators, at once with broad or spread-out currents of cotton (or other material) free from lumps, and thus prevent the 55 clogging of the cotton-gin receiving it.

In Fig. 3 are shown three openings and sliding boards; but any desired number may be used, according to the number of bins or 60 gins in use.

In the modification shown in Fig. 4 the horizontal portion of the apron shown in Fig. 1 is dispensed with, as the elevator is simply intended to elevate cotton above a cotton-gin to be located adjacent to the hopper A². The 75 elevator-belt B simply passes over and around the guide-pulleys B'.

To regulate the amount of cotton elevated, there is mounted in adjustable bearings a shaft, C', carrying a revolving apron, c', to which 80 motion is given in a direction contrary to the current of ascending cotton by means of the belt D³, (shown in dotted lines,) passing also around a pulley mounted upon the shaft D.

The elevator is not only in front of the gin 85 G, but so far from it that the operator may pass between the elevator and the gin, the cotton passing over his head and forward to the breast of the gin.

The elevator is so constructed that it will 90 stand without movable legs and be driven either from the gin or from any other convenient point.

Having now fully described my invention, I 95 claim—

1. In a cotton-elevator, the vertical casing A, elevator-belt B, its shafts provided with sprockets D' and D², chain D³, and rollers B' and C', in combination with the belt C², provided with rake-teeth c², substantially as and 100 for the purpose described.

2. In a cotton-elevator, the combination of the horizontal casing A', provided with openings E in the bottom thereof, and the endless

elevator-belt A, with sliding boards E', having their inner end cut diagonally, substantially as and for the purpose described.

3. The combination of the elevator-casings 5 A and A', provided with openings E, and sliding boards having their inner ends cut diagonally, rollers B', elevator-belt B, with the belt c' on the outer side thereof, and hopper, substantially as and for the purpose described.

10 4. In a cotton-elevator, the combination of the vertical casing A, elevator-belt B, its shafts provided with sprockets, chain D², and rollers B' and C', with the revolving rake having teeth c², revolving in a direction contrary to the 15 current of ascending cotton, substantially as and for the purpose described.

5. The combination of an endless-belt elevator with a cotton-gin so arranged together that while the elevator receives the cotton in front of the gin a passage is left for the operator immediately in front of the gin, and the cotton is conducted to the gin over the head of said operator, substantially as described. 20

In testimony whereof I affix my signature in presence of two witnesses.

ABNER D. THOMAS.
